UNDERGARMENT

Merton M. Lloyd, Piqua, Ohio, assignor to The
Atlas Underwear Company, Piqua, Ohio, a cor-
poration of Ohio

Application February 9, 1945, Serial No. 577,023

4 Claims. (Cl. 2—224)

1

This invention relates to nether garments for men and is concerned more particularly with a novel garment of the briefs type which is attractive in appearance, is comfortable to wear, and can be made at relatively low cost. The new garment is made of knitted material, so that it will fit the body snugly, and it is so constructed that access to the interior of the garment, while it is being worn, may be readily had by displacement of certain parts and without undoing fastenings of any kind. The displaced parts are normally held in such relation by the stresses imposed upon them by the stretching of the garment by the body of the wearer, that they overlap and close the access opening. Accordingly, upon release of the displaced parts, they return quickly to their original positions and remain there under normal conditions.

The new garment includes a back section and right and left front sections connected along their outer side edges to the side edges of the back section. One of the front sections overlaps the other along the central area of the garment from top to bottom of the sections and their inner side edges have outwardly concave portions and lie wholly on opposite sides of the central median line of the garment. The concave portions of the inner side edges are free and separable to afford access to the interior of the garment, but, when the garment is being worn, stresses are applied to the ends of the curved portions of the inner side edges of the front sections, which tend to maintain such edges taut and overlapped without gaping.

For a better understanding of the invention, reference may be had to the accompanying drawings, in which

Fig. 1 is a view of the garment in front elevation;

Fig. 2 is a sectional view on an enlarged scale on the line 2—2 of Fig. 1;

Fig. 3 is a rear view with parts broken away;

Fig. 4 is a partial front elevational view of a modified construction.

The garment, as illustrated in the drawings, is made of knitted material having its wales running vertically, so that it is extensible circumferentially of the garment, and it includes a back section 10, a left front section 11, and a right front section 12. The front sections are con-

2

nected along their outer side edges 13, 14 to the adjacent side edges of the back section, and the front and back sections may be integral and cut from a single piece of material or they may be separate pieces connected by seams.

The bottom edge of the back section is formed with a central transverse portion, and on either side thereof, the bottom edge is of curved formation so as to define portions of leg openings 15, 16. The front sections overlap from top to bottom thereof with the inner side edge of section 11 overlying the corresponding edge of section 12 and the inner side edges of the sections lying wholly on the opposite side of the vertical median line of the garment. At their lower ends, the overlapped portions of the front sections are connected to the central portion of the bottom edge of the back section by a seam 17. On either side of the connection, the lower edges of the front sections are of curved formation to define the remainder of the leg openings. The edges of the leg openings are finished by means of hems 18 which are preferably made of a knitted material extensible circumferentially of the openings and may, if desired, include elastic inserts to cause the edges of the openings to cling more closely to the legs of the wearer.

The portion 19 of the inner side edge of front section 11, which extends upwardly from the seam 17 along the edge of leg opening 15 to a point 20 somewhat below the top of that leg opening, is connected to the underlying portion of front section 12. From the point 20, the portion 21 of the inner side edge of front section 11 is free of the underlying front section 12 to the top edge of the sections. Front section 12 similarly has a portion 22 of its inner side edge extending along the edge of leg opening 16 and connected to the underlying front section 11 from the seam 17 to a point 23 on the edge of the leg opening in a horizontal plane through the point 20. From the point 23 up to the top of the front sections, the inner edge of section 12 has a portion 24 which is free of section 11. The portions 21 and 24 of the inner side edges of sections 11 and 12, respectively, are concave toward the adjacent side edges of the garment, and these edge portions are finished with hems 21a, 24a, respectively, which are substantially inextensible lengthwise and serve as a reinforcement.

A waistband 25, which is preferably endless and of elastic material, is attached to the top edges of the front and back sections. At the points where the curved portions 21, 24 of the inner side edges of the front sections meet the waistband, these portions are outwardly inclined and at their lower ends, where they meet the edges of the leg openings 15, 16, the edge portions are again outwardly inclined. With this arrangement, when the garment is put on and the waistband and leg openings are expanded, forces are applied to the opposite ends of each of the curved edge portions 21, 24, tending to pull these edge portions toward the lateral edges of the garment. The forces tend to maintain the front sections in overlapping relation and to hold the overlapped parts in position and prevent their gaping. Access, however, may be readily had to the interior of the garment by separating the overlapping portions of the front sections defined by edge portions 21, 24 and when the displaced parts are released, the forces applied to the edge portions cause the parts to return to their original overlapping relation.

If desired, a row of stitching 26, 27 may be applied to each of the front sections to connect the curved edge portion thereof to the edge of the leg opening lying on the opposite side of the central median line of the garment and such stitching tends to prevent sagging of that part of the front section lying below it.

In the garment described, the front sections are made of a single piece of material, but, if desired, the lower end portions of the front sections may be made of pieces separate from the remainder. Such separate pieces are preferably cut with a sloping top edge so that the seams joining them to the remainder of their respective sections serve the purpose of the rows of stitching 26, 27.

The garment shown in Fig. 4 is the same in construction as that above described except that it includes a waistband 28 which has ends 28a, 28b connected to the tops of respective front sections and adapted to be connected in overlapping relation by buttons 29 on end 28b receivable in buttonholes 30 in end 28a.

In all forms of the new garment, the front sections are free of one another from points below the tops of the leg openings to the waistband. The front sections overlap from top to bottom and the minimum overlap occurs where the curved edge portions 21, 24 approach each other most closely. In this region, the front sections may be separated with least displacement of the parts of the garment to afford access to the interior thereof. Under normal conditions of wear, the overlapped parts of the front sections are maintained in that relation by the forces applied to the curved edge portions 21, 24 at opposite ends thereof. These forces applied at the waistband through the reinforcing members 21a, 24a also tend to keep the lower ends of the overlapped parts of the front sections from sagging.

I claim:

1. A nether garment which comprises a back section having a lower edge formed with a central transverse portion and curved portions on either side thereof defining parts of leg openings, right and left front sections connected along their respective outer side edges to the adjacent side edges of the back section, one of the front sections overlapping the other from top to bottom thereof centrally of the garment with the inner side edges of the front sections lying wholly

on opposite sides of the vertical median line of the garment, the overlapping areas of the front sections being connected at their lower ends to the central transverse portion of the lower edge of the back section, each front section having a portion of its inner side edge at the lower end of the section connected to the other section and the remainder of the side edges of the front sections being free, and a waistband connected to the upper ends of the front and back sections, the free portions of the inner side edges of the front sections extending from the leg openings to the waistband and being concave toward the side edges of the garment.

10 2. A nether garment which comprises a back section, right and left front sections connected along their respective outer side edges to the adjacent side edges of the front sections lying wholly on opposite sides of the vertical median line of the garment with one of said edges overlapping the other from top to bottom of the front sections, the lower end portion of the inner edge of each front section being connected to the other front section along an edge thereof and elsewhere being free, the free portions of said inner edges curving inwardly toward each other from the upper ends of the connected portions of said edges and thence outwardly, and a waistband connected to the upper ends of the front and back sections, the lower ends of the front sections being connected to the central portion of the lower end of the back section.

20 3. A nether garment which comprises a back

30 section having a lower edge formed with a central transverse portion and curved portions on either side thereof defining parts of leg openings, right and left front sections connected along their respective outer side edges to the adjacent side

40 edges of the back section, one of the front sections overlapping the other from top to bottom thereof centrally of the garment with the inner side edges of the front sections lying wholly on opposite sides of the vertical median line of the

45 garment, the overlapping areas of the front sections being connected at their lower ends to the central transverse portion of the lower edge of the back section, each front section having a portion of its inner side edge at the lower end of the

50 section connected to the other section and the remainder of the side edges of the front sections being free and separable to afford access to the interior of the garment, reinforcing members disposed along the entire length of the inner side edge of each front section, and an extensible waistband connected to the upper ends of the front and back sections.

55 4. A nether garment which comprises a back section having a lower edge formed with a central transverse portion and curved portions on either side thereof defining parts of leg openings, right and left front sections connected along their respective outer side edges to the adjacent side edges of the back section, one of the front sections overlapping the other from top to bottom thereof centrally of the garment with the inner side edges of the front sections lying wholly on opposite sides of the vertical median line of the

60 garment, the overlapping areas of the front sections being connected at their lower ends to the central transverse portion of the lower edge of the back section, each front section having a portion of its inner side edge at the lower end of the section connected to the other section and

the remainder of the side edges of the front sections being free and separable to afford access to the interior of the garment, a waistband attached to the upper ends of the front and back sections, the waistbands having overlapping ends terminating even with the upper ends of the inner side edges of the front sections, and means on the overlapping portions of the waistband for securing them together.
